CLAIM

The ornamental design for a selfie light, as shown and described.

DESCRIPTION

FIG. 1 is a perspective view of a selfie light showing my new design;

FIG. 2 is a front view thereof;

FIG. 3 is a rear view thereof;

FIG. 4 is a right side view thereof;

FIG. 5 is a left side view thereof;

FIG. 6 is a top thereof;

FIG. 7 is a bottom view thereof;

FIG. 8 is a top view of a selfie light thereof shown in use with two additional lights shown as broken line environment;

FIG. 9 is a top view of a selfie light thereof shown in use with four additional lights shown as broken line environment;

FIG. 10 is a top view of a selfie light thereof shown in use with three additional lights shown as broken line environment; and,

FIG. 11 is a top view of a selfie light thereof shown in use with five additional lights shown as broken line environment.

The broken lines in FIG. 7 depict portions of the selfie light that form no part of the claimed design. The broken lines in FIGS. 8-11 depict environmental subject matter and form no part of the claimed design.

1 Claim, 6 Drawing Sheets
